UNITED STATES PATENT OFFICE

ALFRED S. GLOSSBRENNER AND GEORGE L. GLOSSBRENNER, OF INDIANAPOLIS,
INDIANA

CALENDAR

Application filed April 9, 1928. Serial No. 268,432.

Our invention relates to improvements in 5
calendars and particularly that type of wall
calendar wherein there is provided a series
of leaves folded upon themselves and forming
a pad, the leaves being so arranged that
when one leaf is turned it exposes a monthly
calendar and at the same time provides a
memorandum pad. In certain of calendars
of this type which are now on the market there
is provided a pad the leaves of which are
adapted to be folded upwardly to expose a
calendar for a month and at the same time
provide a memorandum. The upper portion
of the pad is generally provided with a cover
sheet on which is displayed suitable adver-
tising matter. One of the objections to this
type of pad has been found to be that the
user will not bother to raise the cover sheet
each time the pad is changed and as a re-
sult the cover sheet is hidden by the turned
up sheets, thereby destroying the advertising
value of the calendar.

It is one of the objects of our invention to
provide a calendar of this character whereby
25 the sheets may be unfolded to provide not
only the monthly calendar sheet, but the
memorandum pad, and at the same time un-
folded in such a manner as to insure the dis-
play of the advertising carried on the cover
30 sheet.

In the embodiment of our invention illus-
trated, in the accompanying drawings—

Fig. 1 is a front elevation partly in section,
of a pad embodying our invention;

Fig. 2 is an end view showing the pad fold-
ed in its normal and delivery position;

Fig. 3 is an end view showing certain of
the sheets turned down;

Fig. 4 is a detail sectional view showing
40 the securing eyelet and associated sheets, and

Fig. 5 is a detail front elevation, showing
the manner of securing the pad sheets.

In the structure illustrated we provide a
45 backing sheet 1 which may be formed of rela-
tively heavy paper and is generally scored
or creased along the center at the point 2 so
that the pad may be folded into book form.
This backing forms a support for the calendar
pad which is made up of a series of leaves 3
50 which are secured intermediate of their ends

to the backing sheet by means of staples 4.
Each of the pad sheets above and below the
fold line has printed on one face a monthly
calendar and on the opposite face memoran-
dum data. The sheets are adapted to be 55
folded at a central point as in a book forma-
tion and their free ends are secured to the
backing sheet by an eyelet 7 which passes
through the edges of the backing sheet and
the pad sheets and provides an eyelet by 60
which the pad may be hung from a nail.
That portion of each sheet surrounding the
eyelet is perforated as at 8 to permit the sheet
to be readily disengaged from the eyelet and
turned down.

The entire pad is provided with a cover
sheet 9 which may be secured by a folded rib
of metal 10 to the backing sheet. This cover
sheet in use may be doubled upon itself to
form a pocket 11.

When the pad is initially delivered all of
the sheets are folded in book form, the calen-
dar sheets being secured in this folded pos-
ition by means of the eyelet. When the calen-
dar is hung the backing sheet hangs straight 75
down and the first sheet is released from the
eyelet by tearing at the perforated points.
This permits the first sheet to unfold and drop
down, exposing the first month of the year
and leaving exposed on the back of the next 80
succeeding sheet the memorandum data 5,
which data, however, is protected and covered
by the cover sheet 9. In this manner the cov-
er sheet may never be hidden by the folding
of the pad in use and the advertising value 85
of the calendar is maintained.

We claim as our invention:

1. A calendar comprising a plurality of
calendar sheets secured together intermediate
of their upper and lower edges in book leaf 90
form, a fastener securing the free edges of
said calendar sheets together, said sheets be-
ing perforated around said fastener to per-
mit the same to be torn free therefrom and a
cover sheet secured at its upper edge to the 95
calendar sheets and having its opposite edge
free, said cover sheet being adapted to overlie
the upper half of the calendar sheets when
the same are unfolded.

2. A calendar comprising a plurality of 100
calendar sheets secured together intermediate
of their upper and lower edges in book leaf
form, a fastener securing the free edges of
said calendar sheets together, said sheets be-
ing perforated around said fastener to per-
mit the same to be torn free therefrom and a
cover sheet secured at its upper edge to the 95
calendar sheets and having its opposite edge
free, said cover sheet being adapted to overlie
the upper half of the calendar sheets when
the same are unfolded.

sheets folded at an intermediate line to one side of the middle, a back, fastening means securing the wider sections of the folded sheets to the back along a line parallel with the fold line, a cover sheet overlying the group of folded sheets, and an eyelet passed through and securing together the back sheet, the edges of the entire group of folded sheets and the cover sheet, the narrower section of each of the folded sheets being weakened along a tear line embracing the eyelet.

In witness whereof, we have hereunto set out hands at Indianapolis, Indiana, this 6th day of April, A. D. one thousand nine hundred and twenty-eight.

ALFRED S. GLOSSBRENNER.
GEORGE L. GLOSSBRENNER.
